(57) **CLAIM**

The ornamental design for a pipe for vacuum cleaner, as shown and described.

DESCRIPTION

FIG. 1 is a front, right and top perspective view of a pipe for vacuum cleaner, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a top plan view thereof.

FIG. 8 is a front, right and top perspective view of a second embodiment of a pipe for vacuum cleaner.

FIG. 9 is a front elevation view of the second embodiment of the pipe for vacuum cleaner of FIG. 8.

FIG. 10 is a rear elevation view of the second embodiment of the pipe for vacuum cleaner of FIG. 8.

FIG. 11 is a left side elevation view of the second embodiment of the pipe for vacuum cleaner of FIG. 8.

FIG. 12 is a right side elevation view of the second embodiment of the pipe for vacuum cleaner of FIG. 8.

FIG. 13 is a top plan elevation view of the second embodiment of the pipe for vacuum cleaner of FIG. 8; and,

FIG. 14 is a bottom plan elevation view of the second embodiment of the pipe for vacuum cleaner of FIG. 8.

The broken lines depict portions of the pipe for vacuum cleaner that form no part of the claimed design. The symbolic break lines depict the boundaries of the claim. The area between the break lines forms no part of the claimed design.

1 Claim, 14 Drawing Sheets
